ATTORNEY

UNITED STATES PATENT OFFICE.

HUGO A. BUCCINI, OF PHILADELPHIA, PENNSYLVANIA, ASSIGNOR TO VICTORY LAMP COMPANY, OF PHILADELPHIA, PENNSYLVANIA.

DESIGN FOR AN ELECTRIC-LIGHTING-FIXTURE PANEL.

Application filed December 19, 1927. Serial No. 24,528. Term of patent 3½ years.

To all whom it may concern:

Be it known that I, HUGO A. BUCCINI, a citizen of the United States, and a resident of Philadelphia, county of Philadelphia, State of Pennsylvania, have invented a new, original, and ornamental Design for an Electric-Lighting-Fixture Panel (Case 170), of which the following is a specification, reference being had to the accompanying drawing, forming a part thereof.

The drawing accompanying this application shows an elevational view of the electric lighting fixture panel.

I claim:

The ornamental design for an electric lighting fixture panel as shown.

HUGO A. BUCCINI.
